MULTIPLE SPINDLE ENGRAVING AND THE
LIKE MACHINE TOOLSAllen D. Gunderson, Racine, Wis., assignor to
George Gorton Machine Co., Racine, Wis., a
corporation of Wisconsin

Application October 3, 1949, Serial No. 119,281

27 Claims. (Cl. 33—25)

1

This invention relates to certain improvements in multiple spindle engraving and the like machine tools; and the nature and objects of the invention will be readily recognized and understood by those skilled in the arts involved from the following explanation and detailed description of the accompanying drawings illustrating what I now believe to be a preferred embodiment or mechanical expression of the invention and the several features thereof, from among various other embodiments, designs, arrangements, adaptations, forms, combinations and constructions, of which the invention is capable within the broad spirit and scope thereof as defined by the appended claims.

By my invention I have provided a tracer controlled machine tool organization particularly adapted, but not limited, to engraving operations, which is characterized by the use of multiple cutter spindles with a work table mounted for universal lateral movements relative to the cutter spindles, and a movement transmitting mechanism of the tracer actuated, pantograph type coupled directly to the work table for actuating the table to move simultaneously multiple work pieces mounted thereon relative to the multiple spindles, respectively, in scaled reproduction of the movements of the tracer in scanning a master to be reproduced on the work pieces.

A general object of the invention is to provide a design and arrangement of such a machine organization, and a construction and combination of the components thereof, to present an extremely stable and rigid machine which is highly sensitive and responsive in operation and capable of reproducing with precision and accuracy on a work piece or simultaneously on multiple work pieces, a scaled reproduction in two dimensions of the master design.

And a further general object is to provide such a machine with controls which substantially eliminate the possibility of operator errors, so that reproducing or engraving operations may be carried out on multiple work pieces with a minimum of work spoilage and at relatively high rates of production without requiring highly skilled operators.

Such a machine organization, in carrying out the foregoing general objects, includes the following primary features:

A plurality of self-contained motorized spindle units together with a mounting therefor, by which such units may be individually and independently removed from and replaced in mounted positions, and by which, when mounted,

2

the units are capable of individual and independent adjustments in directions axially and/or radially relative to each other;

5 Mechanism for feeding the multiple cutter spindle units simultaneously in precise synchronization to and from operative working positions relative to multiple work pieces, respectively, mounted on a universally laterally movable work table.

10 Electro-pneumatic mechanism and operating controls therefor, for actuating the cutter spindle unit feeding mechanism.

15 The mounting directly on an adjustable supporting knee structure of a table unit of the universally laterally movable work table type for movement as a unit with the knee structure; and the design and construction of such a work table unit which provides an arrangement of slide rods mounted in linear, antifriction bearing assemblies to provide a minimum friction, highly sensitive mounting for universal, lateral movements of the work piece supporting table component of the table unit.

20 25 The combination with such a "sensitive" type work table, of a pantograph mechanism directly coupled therewith by which the work table is universally laterally movable in scaled reproduction of the movements imparted to the pantograph mechanism by the tracer in scanning a master;

30 The provision for the adjustment bodily of the work table unit with the supporting knee structure in either direction transversely of the general plane of the pantograph mechanism, without changing the position of the pantograph mechanism or disconnecting it from the universally laterally movable work supporting table component of the unit;

35 Mechanism for mounting on the universally laterally movable table component of the work table unit, multiple work pieces in operative relation with the multiple cutter spindles, respectively, and for indexing simultaneously in precise synchronism, such multiple work pieces to present different portions thereof in operative working position relative to the spindle units.

40 45 Electro-pneumatic means for operating the work piece indexing mechanism to effect simultaneous indexing of multiple work pieces.

The system of interlocks for the work indexing actuating means and cutter spindle unit feed actuating means by which work indexing is prevented when the cutter spindle units are fed to and are in positions in operative working relation with the work pieces on the work table, and by which work indexing may be effected only when

the cutter spindle units are in positions removed from operative working relation with the work pieces.

The provision of an indexable master unit for mounting a plurality of different patterns with such master unit mounted for selective indexing to position a desired pattern for scanning by a tracer style mounted for movements between position in scanning engagement with a pattern and position out of scanning engagement with 10 the pattern.

The system of interlocks by which the master unit is locked against indexing when the cutter spindle units are fed to and are in positions in operative working relation with work pieces on 15 the work table, and by which the master unit may be indexed only when the cutter spindle units are in positions removed from operative relation with the work pieces, so that, indexing of the master unit and indexing of the work pieces may 20 be effected simultaneously and only when the cutter spindle units are out of work operating positions relative to the work pieces;

The system of interlocks by which the cutter spindle unit feed actuating means is controlled 25 by the operation of the tracer to and from pattern engaging position, to cause feed of the spindle units to working position with the tracer in pattern engaging position and to cause feed of the spindle units to non-working position when 30 the tracer moves to pattern disengaging position; and by which the spindle unit feed actuating means is rendered inactive to lock the spindle units against feed when the tracer is in disengaged position.

With the foregoing and various other objects, features and results in view, which others will be readily apparent from the following explanation and detailed description of the illustrated example of the invention, my invention consists in certain novel features in design and construction and in combinations and sub-combinations of parts and elements, all as will be more particularly referred to and specified hereinafter.

Referring to the accompanying drawings in 45 which similar reference characters refer to corresponding parts throughout the several figures thereof:

Fig. 14 is a view in vertical, transverse section through the work table and its antifriction slide mounting, taken as on the line 14-14 of Fig. 11, and also showing in vertical, transverse section one of the work mounting units of the work indexing mechanism.

Fig. 15 is a vertical transverse section taken as on the line 15-15 of Fig. 11.

Fig. 16 is a view in side elevation of the left hand end of the cutter spindle head mounting structure, and showing, partly in side elevation and partly in vertical section, the electro-pneumatic spindle feed actuating mechanism.

Fig. 17 is a detail view in horizontal section through one of the cutter spindle unit mounting heads, a gear train of the spindle unit feed being also shown.

Fig. 18 is a view in vertical section through one of the cutter spindle unit mounting heads showing a spindle unit mounted therein in operative engagement with the spindle unit feed mechanism.

Fig. 19 is a vertical sectional view through the master wheel and its mounting, the indexing plunger and plunger lock, and the tracer arm and tracer of the pantograph mechanism.

Fig. 20 is a purely schematic diagram of the electrical circuits and controlling interlocks therefor, and of the electro-pneumatic spindle feed and work indexing mechanism operating means and the air line system therefor.

An example embodiment of the invention and of the various features thereof, is illustrated and disclosed herein in the form of a tracer controlled, multiple cutter spindle engraving machine, designed for engraving simultaneously on multiple work pieces a scaled reproduction of a selected pattern from a series of patterns mounted on an indexable master unit. The invention is not, however, limited or restricted as to all of its features or as to all combinations or sub-combinations thereof, to the example machine hereof, or to embodiment in or adaptation to machine organizations of either the multiple spindle type or of the engraving type.

General organization

The example machine is of the vertical column and knee type in which a vertical column 10 extends vertically upwardly from a base 11 and mounts at the forward side thereof a vertically adjustable knee K. A slide block 10a is mounted 75 at the forward side of column 10 for horizontal

adjustments in either direction on a dovetail slide 10b (see Fig. 4) at the upper end of the column. Slide block 10a provides at the forward side thereof a vertically disposed dovetail slide 10c which fits into a complementary vertical slide way formed in the rear side of structure K for adjustment of the knee structure on the slide block upwardly or downwardly relative to column 10. The knee K is vertically adjustable upwardly or downwardly by means of a vertical feed screw 10d carried by slide block 10a and rotated from hand wheel 10e carried by the knee. Horizontal adjustment transversely of the knee K on column 10 is effected through the medium of a lead screw 10f rotated by a hand crank 10g.

The column 10 mounts or provides at its upper end a forwardly, horizontally extended cutter spindle unit mounting head structure 12, which in this example is of greater width than the width of the column structure, as will be clear by reference to Fig. 2. At the forward, vertical side of structure 12, a series of vertically disposed spindle unit mounting heads H are adjustably mounted for receiving in vertically disposed position therein a plurality of motorized cutter spindle units S, respectively.

A work table unit T which provides a universally laterally movable work table mounting component, is mounted in horizontally disposed position directly on the upper side of the vertically adjustable knee K and is adapted to be carried by and moved vertically upwardly or downwardly as a unit with the knee toward or from spindle unit mounting heads H and the spindle units S mounted therein. The table unit T is slidably mounted on knee K by a dovetail slide 14 which is received and slidably fitted into a complementary dovetail groove 14a formed in the under side of the base of table unit T. Thus, the table unit T may be adjusted on knee K in directions inwardly toward or outwardly from the column structure 10. Adjustments "in" or "out" of table unit T are effected by a usual feed screw 14b mounted on knee K, disposed longitudinally of slide 14, in threaded engagement with a usual feed screw nut (not shown) carried by table unit T. Feed screw 14b is rotated in either direction by a hand crank 14c at the outer end thereof at the forward side of knee K (see Figs. 1 and 5).

A movement transmitting pantograph linkage mechanism P is pivotally mounted and hung from a fixed vertical pivot supported from column structure 10, with the pantograph mechanism P disposed horizontally and positioned at one side of the machine adjacent one end of the table unit T, in this instance the right hand side. Pantograph mechanism P is operatively coupled directly with the adjacent end of the universally laterally movable work piece mounting component of table unit T, for transmitting in scaled relation to such table component, the movements transmitted to the pantograph mechanism by a tracer style A mounted on and carried by a tracer arm of the pantograph mechanism.

At the forward, right hand side of the machine a master wheel M is mounted in vertically disposed position for rotation about a horizontal axis on the forward end of an arm structure 15, which extends horizontally forwardly from the right hand side of column structure 10 (see Figs. 3 and 4). The master wheel M is adapted to mount on and around the periphery thereof, a

series of patterns for selective positioning by indexing rotation of said master wheel for tracing engagement by the tracer style A.

5 A multiple work piece mounting and indexing mechanism B for indexing simultaneously work pieces mounted thereon, is mounted on the universally laterally movable work table forming component of table unit T. This mechanism B provides a plurality of indexable work holding fixtures on which may be mounted the work pieces W (see Figs. 1 and 4). The work pieces W are positioned by the work holding fixtures with portions of the upper sides or edges thereof in vertical alignment with rotary engraving or cutting tools C mounted in the lower ends of the cutter spindles of the motorized spindle units S.

20 A pneumatic cylinder and piston unit D (see Figs. 4 and 16) is mounted on and forms a component of the work holding and indexing mechanism B, for operation to actuate the work indexing mechanism to index work pieces W mounted thereon into positions to present portions of the peripheral edges of such work pieces for working engagement with the engraving tools or cutters C.

25 An air cylinder and piston unit E is mounted on the left hand side or end of head structure 12 (see Fig. 4) for operation to actuate the feed mechanism for the motorized spindle units S, to effect feed of these units simultaneously toward or from work table unit T to thereby project and retract the spindle mounted cutting tools C to and from working engagement with work pieces W mounted on the work holding and indexing mechanism B.

30 The operation of the pneumatic cylinder unit D for actuating the work piece indexing mechanism B, is controlled by a solenoid operated air control valve unit F located in the air lines to the unit D (see Fig. 3). The actuation of control valve unit F is controlled by the energization and de-energization of the solenoid of the unit which in turn is controlled by suitable interlock switches, to be identified and described hereinafter, in the electrical circuits to the solenoid of the valve unit.

35 The cylinder and piston unit E for actuating the feeding mechanism for the spindle units S, is controlled by a solenoid actuated air control valve unit G located in the air lines to unit E. The actuating solenoid of the air control valve unit G is energized and de-energized under the control of interlock switches, to be identified and described hereinafter, connected into the electrical circuits to the solenoid of valve unit E.

Multiple spindle units and their mounting

40 In the example machine a series of four (4) self-contained, motorized spindle unit S are provided for mounting in vertically disposed position in the heads H. The heads H are adjustably mounted on the forward side of structure 12 in vertically disposed positions above the work table unit T.

45 Referring now to Figs. 16, 17 and 18, in connection with Figs. 1-4, the motorized spindle units S are identical in design, construction and dimensions and are interchangeable in the heads H. Each spindle unit S comprises a circular casing 20 within which there is mounted and contained a motorized spindle assembly 21, which includes a motor and the cutter spindle 22 driven thereby and rotatively journaled therein in position disposed axially of the casing. The motorized spindle assembly 21 is slidably

mounted and contained within the casing 20 for movement axially in either direction therein. The position of the spindle assembly axially of casing 20 is adjustably determined by a micrometer adjusting mechanism 23 mounted at the upper end of casing 20 on an end cap 20a.

The arrangement of each motorized spindle unit S is such that the motorized spindle assembly 21 therein is located extending outwardly through one end (the lower end) of casing 20, through the cutter spindle 22 projecting outwardly with the cutter spindle 22 projecting outwardly beyond the assembly 21. The outer end of cutter spindle 22 provides the operating end or nose of the spindle and mounts thereon any suitable cutting or engraving tool receiving and securing chuck or holder 22a, in which there may be mounted a cutting tool C.

Each of the cutter spindle unit mounting heads H is formed with an axial bore or passage 30 extending vertically therethrough and having a constant internal diameter which is substantially the same as the external diameter of the casing 23 of spindle unit S, so that, a unit S may be mounted therein in position extending therethrough with a slideable or running fit. A mounting base 31 is provided extending laterally or radially from the rear side of a head H, and this base 31 includes the opposite side vertical flanges 32 by which the head is adjustably mounted on the forward side of structure 12.

The forward side of the head mounting structure 12 is formed with a horizontal, longitudinally disposed channel 12a therein extending thereacross. Channel 12a is open at its forward side through the vertical, outer side surface 12b at opposite sides of channel 12a is formed to provide seating surfaces to receive and against which the base flanges 32 of heads H are adjustably secured. T-bolt slots 12c are formed in head structure 12 at opposite sides of channel 12a opening forwardly through seating surface 12b. T-slots 12c are disposed in parallel relation and extend longitudinally and substantially throughout the width, of the forward end of structure 12.

The spindle mounting heads H are adjustably mounted side by side in positions spaced along and extending forwardly from head structure 12, and with the bores or openings 30 therethrough disposed vertically and in parallelism, by securing the base flanges 32 of each head to the seating surfaces 12b by the T-bolts 33 which are received and secured in the T-slots 12c. Thus the spindle unit mounting heads H are independently adjustable relative to each other horizontally along head structure H, and radially or laterally relative to each other, by loosening the T-bolts 33 of a unit, and then sliding the unit the required distance to the right or to the left to its desired position of adjustment on structure 12.

A motorized spindle unit S is mounted in a head H in vertically disposed position extending through and slidably received in the vertical bore 30 of the head and with the operating nose end 22 of the motorized spindle assembly 21 projected downwardly a distance below the head. A spindle unit S is maintained in mounted position in the head H against rotational movements relative thereto by a positioning pin 34 which is secured extending through the lower forward or front portion of head H into and disposed radially of a spindle unit mounting bore 30. Each spindle unit S is provided in the forward side of its case 20 with a vertically disposed slot 24 into which the inner projected end of 75 mounting head H.

the positioning pin 34 of the head H is slidably received. The positioning slot 24 of each spindle unit opens at its lower end through the lower end of casing 20 to permit of lifting a unit S vertically upwardly to remove the unit from a mounting head.

Vertical bores 35 are formed in each mounting head H opening through the upper side edge thereof and extending a distance downwardly into the head. These vertical bores 35 are located in diametrically opposite positions in a head H between the base 31 and the forward side of the head. A coiled expansion spring 36 is positioned in each of the bores 35. Plunger forming rods 37 are mounted in bores 35 and at their upper ends are engaged by the end cap 28 of the unit. Rods 37 are formed at their lower ends to provide the heads 37a of an external diameter to be received in and form a free fit with the bores 35 of the heads H for vertical reciprocation thereof in bores 35.

In mounted position of a spindle unit S in the bore 30 of a head H, the rods 37 extend downwardly into head bores 35, respectively, with the heads 37a thereof engaged with the upper ends of spring 36 and with these springs confined under compression between the lower end walls of bores 35 and the plunger heads 37a, so that, the rods are spring biased upwardly in engagement with cap 28. By this arrangement there is provided an anti-backlash means for the spindle unit feeding mechanism, as will be referred to hereinafter.

The casing 20 of each motorized spindle unit S is provided with or has machined therein, vertically disposed rack teeth 38 in the rear side thereof disposed in the vertical plane of the diameter which passes through the positioning slot 24 in the forward side of the casing.

Spindle unit feed mechanisms

Each head H mounts in the flanged base thereof a gear train consisting of a pair of normally meshed gears 40 and 41. Referring to Fig. 17, the gear 41 is located in a bore 41a in base 31, which bore is horizontally disposed transversely relative to the base. Bore 41a opens through one side of the base 31, and a circular block or plug 42 is threaded into the open end of the bore. Plug 42 has an axial bore which slidably and rotatably mounts and receives therein one end of a shaft 43 on which gear 41 is fixed for rotation with the shaft. The opposite end of shaft 43 extends through and is slidably and rotatably received in a bore in the opposite side of base 31, and projects outwardly a distance therebeyond to provide a push button or plunger 43a. A coiled expansion spring 44 is mounted on and around shaft 43 under compression between block 42 and the adjacent side of gear 41. Thus, gear 41 is spring biased inwardly and normally maintained in position in mesh at its forward side with the rack teeth 38 of spindle unit S mounted in the head H, and at its rear side with the gear 41.

By the foregoing arrangement, a motorized spindle unit S may be readily mounted in and removed from a head H by pressing inwardly on the push button end 43a of shaft 43 to thereby displace that shaft and the gear 41 outwardly from its position between and in mesh with gear 40 and rack teeth 38 of the spindle unit, to a position out of mesh therewith. With gear 41 in displaced, disengaged position clear of spindle unit rack teeth 38, a cutter spindle unit S may then be readily inserted in or removed from a

Gear 40 is rotatably mounted on a shaft 45 which is mounted in the inner, flanged portion of base 31 of a head H, in horizontal position parallel with shaft 43a. The gear 40 is rotatably received in a vertically disposed slot or passage 40a formed through the inner flanged portion of base 31. Passage 40a opens at its forward side into bore 41a and at its rear side into the channel 12a in the forward side of head mounting structure 12. Gear 40 has a diameter such that it projects a distance inwardly into the channel 12a when the head H in which it is mounted, is attached in mounted position on structure 12, as will be clear by reference to Figs. 17 and 18.

A long gear 46 in the form of a toothed shaft or spindle, is mounted in horizontal position extending longitudinally through channel 12a of structure 12, and is journaled at its opposite ends in end walls at the opposite ends, respectively, of the channel. This long gear 46 is formed, in this example, with longitudinally disposed teeth forming ribs or splines 46a there-around which extend throughout the length of the gear within the channel 12a. Shaft gear 46 is mounted in position with its axis in the horizontal plane passing through the axes of gears 40 and 41, for meshing engagement by the inner side of a gear 40 in mounted position of a spindle unit head H on structure 12.

With the multiple spindle heads H in mounted adjusted position on and along the seating surfaces 12b, each of the gears 40 of a head carried feed gear train is thus engaged in driven connection at its inner side with the long shaft gear 46, so that, rotation of gear 46 will effect rotation simultaneously of the head mounted feed gear trains. With cutter spindle units S mounted in the heads H with the rack teeth 38 of such units in mesh with the inner gears 41 of the feed gear trains, rotation of shaft gear 46 in a clockwise direction will rotate gears 41 of the feed gear trains in a clockwise direction to feed the cutter spindle units S downwardly to operative, working positions, while rotation of shaft gear 46 in a counterclockwise direction will effect feed of the spindle units S upwardly to raised, non-working positions.

The arrangement of the spindle unit carried rods 35 and head mounted springs 36, is such as to function to eliminate backlash in the feed gear trains and shaft gear 46, and thus insure precise synchronization of the feeding movements imparted simultaneously to the spindle units S by rotation of the shaft gear 46. With the shaft gear 46 toothed throughout the length thereof within channel 12a by the unbroken, parallel teeth 46a, any mounting head H may be individually adjusted in either direction horizontally along the mounting seats 12b of structure 12, with the inner gear 40 of the feed gear train merely sliding along shaft gear 46 in continuous mesh therewith. Such an adjustment of a head may be effected independently of the other heads H, and without disconnecting the driving connection between the gear 40 of the adjusted head and the shaft gear 46, so that in any adjusted position laterally of a head H the feed gear train thereof will be automatically maintained in driving connection with shaft gear 46.

In the machine of the example, four (4) mounting heads H are shown, but the width of head mounting structure may be considered to be such as to present seating surfaces 12b of a length to accommodate and mount six (6) of the heads H. Obviously any lesser number of the

heads H may be employed if desired, and spindle unit mounting heads of smaller width dimensions than those of heads H of this example, may be utilized, so that, a greater number of heads may be mounted on the seating surfaces 12b of structure 12. Conversely heads of greater dimensions may be employed, so that the maximum mounting capacity of structure 12 will be reduced. Or a greater width may be provided for mounting structure 12 to form head seating surfaces of greater length to accommodate a greater number of heads H.

Spindle unit feed actuating means

The shaft gear 46 which drives the feed gear trains 40-41 of each spindle unit mounting head H, is rotated in either direction by the pneumatic cylinder and piston E. Referring to Fig. 16, this unit E is mounted at the left hand side of head mounting structure 12, being suitably enclosed or encased, and comprises an air cylinder 50 disposed in a forwardly, upwardly inclined position and mounting therein a piston 51 with a piston rod 52 extending outwardly therefrom through the forward head 53 of the cylinder.

The outer, forward end of the piston rod 52 is pivotally coupled by a link 52a to the upper end of a crank arm 53 which is attached to and extends upwardly from the outwardly extended, adjacent exterior end of the shaft gear 46. The coupling linkage of piston 52 to shaft gear crank 53 is such, that with piston 52 at the end of its rearward, downward stroke, shaft gear 46 is rotated counter-clockwise to position with spindle units S in heads H fed upwardly to raised, non-working positions, while with piston 51 at its limit of forward, upward movement, shaft gear 46 is rotated in a clockwise direction to feed the cutter spindle units downwardly to operative, working positions.

The inner, lower end of cylinder 50 is closed by a head 54. Head 54 is provided with an air intake-exhaust passage 57 therethrough, opening at its inner end into cylinder 51 and at its outer end opening through the peripheral side wall of head 54 where it is connected with an air supply-exhaust line 58.

A collar 59 is secured on rod 52 adjacent the forward upper end thereof. This collar 59 provides at the inner side thereof an annular abutment surface 59a therearound which is precisely machined or formed to fit and engage against a complementary abutment surface 56b formed at the outer side of the upper end cylinder head 56. Surface 56b thus forms an accurate and precisely located abutment stop for engagement by surface 59a of collar 59 to limit the inward stroke of piston 51 to thereby determine accurately the maximum raised positions of spindle units S.

A coiled expansion spring 55 is mounted on and around piston rod 52 between piston 51 and the inner side of the outer end cylinder head 56. Spring 55 acts to continuously bias piston 51 and rod 52 rearwardly and downwardly in cylinder 50 to its limit position with abutment surface 59a of collar 59 engaged against stop surface 56b of head 56.

Forward, upward movement of piston 51 is effected by admitting air under pressure into the lower end of cylinder 50 through passage 57, to develop pressures acting on piston 51 of a magnitude to overcome the biasing forces of spring 55 to thereby force piston 51 and rod 52 upwardly to effect feed downwardly of the spindle units S to operative, working positions. The inner side

11

of cylinder head 56 provides an accurately formed abutment surface 56a for engagement by a complementary surface 51b formed on and around the adjacent side of piston 51, to thus provide an abutment stop for accurately limiting forward movement of the piston and downward feed thereby of the spindle units S in the head H. These abutment or stop surfaces 51b and 56a are accurately located and positioned to give the cutter spindle units S a precise, predetermined maximum lowered or "depth" position.

It is to be noted that in Fig. 16 the cylinder and piston unit E is shown in air pressure actuated position with the cutter spindle units S fed downwardly and being maintained by air pressure in cylinder 50 in lowered, working positions for engaging cutter tools C in the spindles 22, with work pieces W on the work holding and indexing mechanism B. When it is desired to feed the spindle units S upwardly to raised positions, the air supply through supply line 58 is cut off and the line is then opened to atmosphere for release of pressure in and exhaust of air from cylinder 50, under the action of biasing spring 55, which then acts to force piston 51 rearwardly to rotate shaft gear 46 in a direction to raise the cutter spindle units S through the operation of the feed mechanism.

Each of the cutter spindle units S is a self-contained, motor driven unit and each is mounted operative position in its head H is supplied with electrical current by a flexible conductor cable L. These individual circuit cables L to the spindle units S, are each detachable from electrical connection with the motor of its unit and from the unit, when it is desired to remove a unit from a mounting head H. The cables L extend to a switch panel LS which mounts a series of four (4) switches, S1, S2, S3 and S4, for selectively opening and closing the supply circuits through the cables L to the units S, respectively. Thus, the motorized spindle units S may be individually, selectively operated or cut off by the operator from the switches on the switch panel LS. In this instance this panel, with the switch actuating levers of the switches, is mounted on the right hand side of the head mounting structure 12, with the switch operating levers in position accessible at the exterior thereof, as will be clear by reference to Fig. 3. The switches of switch panel LS are connected with a suitable source of electrical current (not shown) in the usual manner for supplying current through cables L to the motors of the spindle units S.

The sensitive work table unit

The work table unit T which is mounted directly on and is vertically adjustable as a unit with the knee K, is of the "sensitive" or so-called "duplicator" table type and provides at its upper side the movable work piece supporting and translating table component 80 mounted for universal lateral movements in a horizontal plane. Referring now to Figs. 11 through 15, in connection with Figs. 1 and 4, the table unit T includes a base plate 61 which is directly mounted on knee K for adjustment thereon in the transverse or "in" and "out" direction relative to the machine, by the dovetail slide 14 on knee K, which is slidably received in the dovetail groove 14a at the under side of base plate 61.

The base plate 61 is provided along and adjacent each opposite, transverse side edge thereof with a series of upstanding lugs, which in this

12

instance include a forward lug 62, an intermediate lug 63, and a rear lug 64, as will be clear by reference to Fig. 11. The lugs 62, 63 and 64 of each series, are spaced and aligned transversely of base 61 and are provided with transversely disposed, axially aligned horizontal bores therethrough. A rod member 65 is secured extending through the bores of the aligned lugs at the left hand end of base 61 with the opposite ends of the rod secured in the forward and rear lugs 62 and 64, respectively, and with the intermediate portion of the rod extending through and intermediately supported by the lug 63. An identical rod member 66 is similarly mounted and secured in the series of base lugs 62, 63 and 64 at the right hand end of the base plate 61. Thus there is provided at opposite ends of base 61 the rods 65 and 66 which are disposed horizontally in parallelism with their axes in the same horizontal plane and extending transversely of base plate 61 to define straight line paths.

A carriage or cradle 70 of generally rectangular plan form is provided having longitudinal and transverse dimensions such that the cradle may be supported in position between rods 65 and 66 for limited movements in either direction transversely thereon above base plate 61 in directions "in" or "out" relative to the machine. At its opposite ends cradle 70 includes the upstanding flanges 71 forming vertical end walls from the outer side of which extend the spaced arms 72 providing at their forward lower ends the anti-friction bearing mounting bolsters 73. Each pair of bearing bolsters 73 is formed with axially aligned, horizontally disposed bores therethrough.

The bearing bolsters 73 at the left hand end of cradle 70 mount therein the linear, annular form antifriction bearing assemblies 65B which are mounted on and slidably receive therethrough the rods 65 at the left hand end of base plate 61 with the forward bearing bolster 73 and its contained linear bearing positioned intermediate rod supporting lugs 62 and 73 and with the rear bearing bolster 73 and its contained linear bearing mounted on the rod 65 between the intermediate rod supporting lug 63 and the rear lug 64. The spaced bearing bolsters 73 at the right hand end of cradle 70 mount therein the linear, annular form antifriction bearing assemblies 66B which are mounted on and slidably receive therethrough the rod 66 at the left hand end of base plate 61, with the forward bearing bolster 73 and its linear bearing positioned between the forward and intermediate rod supporting lugs 62 and 63, and with the rear bolster 73 and its linear bearing mounted on the rod 66 between the intermediate and rear rod supporting lugs 63 and 64.

By the foregoing mounting and arrangement, the cradle 70 is mounted and supported at its opposite ends in a horizontal position from the spaced parallel rods 65 and 66, constrained or limited to straight line movements on the rods transversely across base 61, in directions "in" and "out" relative to the machine. The linear bearing assemblies 65B and 66B provide minimum friction slidable mountings for the cradle 70 on rods 65 and 66, so that, the cradle is highly sensitive and responsive to movement by the application thereto of forces of relatively small magnitudes.

Adjacent the rear, longitudinal side of cradle 70 there is mounted, extending between the opposite, upstanding flanges 71, a rod member 74. Rod 74 is secured at its opposite ends in aligned

bore 74a in opposite end flanges 71 with the rod in horizontal position with its axis perpendicular to the axes of the parallel, transversely disposed rods 64 and 66. The rod end receiving bores 74a are located at the rear sides of and opposite bearing bolster supporting arms 72, respectively, and these bores may be extended outwardly through arms 72 for ready assembly and removal of rod 74 to and from mounted position. Suitable set screws 74d may be employed for 10 securing the rod ends in flanges 71.

A rod member 75 identical with rod 74, is mounted in position along and adjacent the forward longitudinal side of cradle 70 in horizontal position parallel with the rearwardly mounted rod 74. Rod 75 is secured in mounted position with its opposite ends received in bores 75a of flanges 71 by set screws 75d. The bores 75a may be extended outwardly through the adjacent arm 72, respectively, to permit of ready assembly and removal of the rod. The cradle 70 may be provided with upstanding lugs 76 intermediate the opposite end flanges 71 for receiving therethrough and providing intermediate support to the forward and rear rods 74 and 75, respectively.

The work piece mounting and translating table component of member 80 of the table unit T, is slidably mounted on the parallel rods 74 and 75 and is constrained by these rods to straight line movements in opposite directions in directions longitudinally of the machine and perpendicular to the path of "in" and "out," transverse movements of cradle 70 on the rods 65 and 66.

The table 80 is provided with spaced lugs 81 depending therefrom adjacent the rear longitudinal side thereof with each of these lugs mounting therein a linear, annular type antifriction bearing assembly 74B. These bearing assemblies are mounted on and slidably receive therethrough the rod 74 with lug 81 and its bearing 74B located between the left end flange 71 and intermediate supporting lug 76, and the other lug 81 and its bearing 74B positioned on rod 74 between the right hand end flange 71 and the intermediate rod supporting lug 76.

A pair of depending, spaced lugs 82, identical with lugs 81, are provided at the under side of table 80 adjacent the forward longitudinal side thereof. Each of these lugs 82 mounts therein a linear, annular type anti-friction bearing assembly 75B, with these bearing assemblies mounted on and slidably receiving therethrough the forwardly located rod 75 of cradle 70. One lug 82 with its linear bearing 75B is positioned on rod 75 intermediate the left hand end flange 71 of the cradle 70 and the intermediate supporting lug 76, while the other lug 82 and its linear bearing 75B are located on rod 75 intermediate the right hand end of flange 71 and the intermediate supporting lug 76.

Each of the bearing assemblies 65B, 66B, 74B and 75B is identical and in this example, is comprised by a known commercial type of linear, annular or sleeve form of antifriction bearing assembly. The construction of the example bearing assembly is illustrated in Fig. 13, and comprises a sleeve 77 within which there is concentrically mounted and confined a tubular retainer 78 which receives and through which a rod or shaft is mounted. The retainer 78 is provided with and mounts a plurality of oblong circuits of antifriction balls 79. Each of the ball circuits 79 presents two (2) straight sides, with one straight side 79a in bearing contact between an inner surface of the ball bushing 75 and

sleeve and the rod or spindle extending through the assembly. The antifriction balls in the remainder of each circuit are free to roll unloaded, in clearance provided in the sleeve.

5 The horizontally positioned work piece mounting table component or member 80 of table unit T is thus movable transversely with the cradle 70 as a unit, "in" and "out" relative to the machine on and with the table 80 and cradle 70, constrained to straight line paths by the spaced, parallel rods 65 and 66. Table 80 is also movable on and independently of cradle 70 in either direction longitudinally of the machine, on and constrained to straight line paths by the spaced, parallel rods 74 and 75 which are positioned with their axes perpendicular to the straight line paths of transverse movements of the table 80 and cradle 70 on rods 65 and 66. And, by simultaneous compound movements of the table 20 80 and of the cradle 70 along the pairs of rods 65—66 and 74—75, respectively, the table is thereby universally laterally movable on base 61 in one plane, in this instance, a horizontal plane.

The table 80 is provided with the usual T-slots 80a in the upper side thereof extending longitudinally across the table for the purpose of mounting on the table, work pieces or work piece holding fixtures.

Due to the mounting of the cradle 70 and the 30 table 80 by means of the linear, antifriction bearing assemblies 65B, 66B, 74B and 75B slidably mounted on the respective supporting track forming rods 65—66 and 74—75, the table 80 is rendered extremely sensitive and highly responsive to table moving forces and to the directions of such forces, applied to the table. The construction and mounting of the base 61, cradle 70 and the table 80, together with the mounting arrangement of the base carried rods 65 35 and 66 and the cradle carried rods 74 and 75, together with the use of commercially available types of linear, antifriction bearing assemblies, make it possible to construct and to assemble such table units at relatively low manufacturing 40 costs by eliminating the necessity for manufacturing specially designed and constructed antifriction bearing slide arrangements for the table unit components, while at the same time providing a construction and assembly which 45 is precise and highly sensitive under production 50 conditions of operation and use, with long wear and with maintenance reduced to a minimum.

The table unit itself, together with the combination thereof with the supporting or knee 55 structure K, by which the table unit T is directly mounted on the knee, provides compactness in the direction transversely of the unit, in this instance in the vertical dimension, so that a machine with which the unit and its 60 supporting structure are used, has an increased capacity for mounting a wider range of sizes of work pieces.

A table unit T of the invention is in no sense 65 limited or restricted to adaptation and use with the machine of this example, or to the combinations in which it is found in this example machine. Table units of the invention are intended for and are adapted in the form here shown, or in various modifications thereof, to 70 general use as a universally, laterally, movable "sensitive" type of work table.

No claim to the sensitive work table unit per se, except as a component in the combinations in claims hereof, is made herein, as such sensitive work table unit and the construction and com-

15

binations of elements thereof, is disclosed and claimed in my copending U. S. patent application Serial No. 359,581, filed as a division of this application.

The pantograph and sensitive table combination

The pantograph mechanism P is of the parallelogram linkage type, and is suspended from a fixed pivot supported from the machine frame structure at the right hand side of the machine, with the pantograph positioned in a horizontal plane parallel with the plane of the universally laterally movable, "sensitive" work table 80. The pantograph mechanism P so positioned is operatively coupled with the right hand end of table T for translating and transmitting to the table 80 in scaled reduction, the movements of the pantograph controlling tracer A as this tracer scans the pattern on the master unit M.

Referring to Figs. 5 through 10, in connection with Figs. 1, 2 and 3, the pantograph mechanism P comprises the spaced, parallel, inner slide bar 90 and outer bar 91, and the spaced, parallel forward and rear links 92 and 93, pivotally coupling and connecting bars 90 and 91 to form the parallelogram linkage in the usual manner. The forward link 92 constitutes a slide bar, while the outer bar 91 is forwardly extended to constitute a tracer arm 94 which mounts at its forward end the tracer unit A.

The pantograph P is pivotally supported and hung from a vertically disposed pivot pin or stud 95 which is carried in and depends from the outer end of a forwardly and outwardly extended hanger arm 96 of a bracket structure 97 which is supported on the horizontally disposed upper side surface of the mounting base 16, by which the master wheel mounting arm 15 is attached to the right hand side of the frame structure of the machine. Base 16 is provided with a T-slot 16a in the upper horizontal surface thereof which is disposed transversely of the machine. Pantograph mounting bracket structure 97 is adjustably secured in position on base 16 by a T-bolt 97a attached in slot 16a, to permit of adjustment of the bracket structure with the pantograph P hung therefrom, in either direction transversely relative to the machine.

The vertical pivot stud 95 is journaled in an anti-friction bearing assembly 95a (see Fig. 7) in the bracket arm 96, and this stud mounts at its lower end the slide block 98 within which the slide bar 90 of the pantograph is adjustably secured. Thus, the pantograph mechanism P as a unit, may be adjusted relative to pivot stud 95 to thus adjust the position of the axis of that stud longitudinally of bar 90.

The forward link of slide bar 92 is positioned below bars 90 and 91, and the forward end of bar 90 mounts a fixed pivot pin 90a which depends therefrom and which is journaled in an anti-friction bearing assembly 90b mounted in bar 92, for relative pivoting or rotation of bars 90 and 92, as will be clear by reference to Fig. 7. A slide block 99 is slidably mounted and confined on slide bar 92 in position at the underside of that bar and being slidable longitudinally in either direction therealong.

The rear link 93 of the pantograph mechanism P is positioned below bars 90 and 91. The inner end of link 93 is pivotally coupled to the rear end of link 90 by a pivot pin 90c fixed in and depending from bar 90 and journaled in an anti-friction bearing assembly 93a mounted in link 93, as will be clear by reference to Fig. 8. The outer

16

end of link 90 is pivotally coupled to the rear end of outer bar 91 by a pivot pin 91a fixed in and depending from bar 91 and journaled in an anti-friction bearing assembly 93b mounted in the outer end of link 93, as shown in Fig. 9. The outer end of forward link or slide 92 is pivotally coupled to bar 91 by a pivot stud 91b fixed in and depending from bar 91 and journaled in an anti-friction bearing assembly 92a mounted in the outer end of link or slide bar 92, as shown in Fig. 10.

The pantograph mechanism P is thus adjustable in the usual manner to vary the ratio of scaled reduction of the movements transmitted to the mechanism by the tracer arm 94, by adjusting the bars 90 and 92 in the slide blocks 98 and 99, respectively, to relatively position the axes of pivot pins 95 and 90a along and relative to the longitudinal axes of bars 90 and 92, respectively. In the example hereof, movement in scaled reduction of the movements of the tracer T at the outer end of tracer arm 94, are taken off from the pantograph mechanism at the slide block 99 which adjustably, slidably receives pantograph bar 92.

The slide block 99 is coupled with the universally laterally movable sensitive table 80 by means of a coupling mechanism which permits of vertical adjustment upwardly and downwardly 30 of table 80 with table unit T and knee K as the unit, without displacing or moving pantograph mechanism P from the horizontal plane in which it is hung and supported by the hanger bracket 96. In the particular adaptation of such a coupling mechanism for the example machine, referring now to Fig. 7 in particular, in connection with Figs. 2 and 5, the slide block 99 mounts therein an annular anti-friction bearing assembly 99a of the double bearing type, with the axis of 40 the assembly vertically disposed. A sleeve member 99b is mounted and journaled in its upper end in bearing assembly 99a and depends vertically downwardly therefrom a distance below slider block 99. A headed stud 99c is mounted and received in sleeve member 99b and extends downwardly therethrough to provide an externally threaded lower end on which there is mounted a fastening nut 99d to engage and secure the stud and sleeve together as a unit assembly journaled in bearing 99a.

An outwardly extended, horizontally disposed rod member 83 is clamped at its rear end on the sleeve in stud assembly 99b-99c, with its axis parallel with the transverse axis of the machine. 55 The forward end length rod member 83 is formed of a reduced external diameter. A link member 84 is pivotally mounted on the reduced diameter portion of rod member 83, and a coiled expansion spring 85 is mounted on member 83 between the shoulder 83a formed at the inner end of the reduced diameter portion and the inner side of link 84.

The outer end of the reduced diameter portion of rod 83 is provided with external screw threading 83b thereon (see Fig. 5), and a micrometer barrel 86 is threaded onto rod 83 and provides a reduced diameter scale bearing hub portion 86a at the inner side thereof for engagement by the adjacent forward side of link 84. A micrometer scale 86s is provided on and around hub portion 86a with an index line 86b being provided on the upper side of link 84 for selective alignment by rotation of barrel 86 with the micrometer divisions of scale 86s. A lock 70 nut 86c is also threaded on rod 83 at the outer

side of micrometer barrel 86, for releasably locking barrel 86 in an adjusted position. The spring 85 continuously biases link 84 outwardly on rod 83 into adjusted position engaged against micrometer barrel hub 86a. The position of link 84 axially on rod 83 is thus adjustable by adjusting the position of the micrometer barrel 86 inwardly or outwardly on the rod 83.

The inner end of link member 84 is provided with a forwardly extended crank pin or shaft member 87 which is disposed radially relative thereto and which extends forwardly and horizontally therefrom. Shaft 87 is accurately formed and positioned so that its axis is in substantially precise parallelism with the axis of rod member 83 on which the outer end of link member 84 is rotatably mounted.

The right hand end wall of table 80 has the horizontally disposed T-slot 80b therein opening outwardly therethrough, and a bearing block member 88 is adjustably secured in the T-slot 80b in position attached to table 80 for movement therewith as a unit. This bearing block 88 provides a horizontally disposed bearing 88a therein which receives and in which shaft 87 of the coupling link member 84 is journaled for pivoting. Thus table 80 is coupled with the slide block 99 of pantograph mechanism P and is universally laterally movable by universal lateral movements of the slide block by the pantograph mechanism under the control of the tracer T at the forward end of pantograph tracer arm 94. The position of coupling link member 84 relative to slide block 99 and pantograph mechanism P, along the axis of rod member 83 is adjustable by the micrometer adjusting mechanism which includes the micrometer barrel 86.

By the foregoing coupling arrangement, the table 80 may be vertically adjusted upwardly or downwardly without interfering with or changing the position or level at which pantograph mechanism P is hung and supported. On upward or downward adjustment of table 80, the coupling link 84 merely pivots or swings about the horizontal, parallel axes provided by rod member 83 and the shaft or pin 87 which is journaled in the bearing block 88 carried by table 80.

The table unit T is also capable of adjustment transversely and/or longitudinally with the knee as a unit on the knee slide 14 and on the column slide 105, while the pantograph mechanism P is adjustable transversely of the machine by adjusting the supporting bracket 96 on base member 16.

The combination of the universally laterally movable table with its minimum friction mounting comprised of the rods and linear antifriction ball type bearing assemblies, together with the pantograph mechanism P with its antifriction bearing pivots, substantially eliminates all looseness and play to thus insure precision reproduction with minimum inertia and highly sensitive responses as precise movements in scaled reduction by the table 80, to movements of the pantograph mounted tracer on the pantograph controlling tracer arm 94.

Tracer and indexable master units

Referring to Fig. 19, the tracer unit A embodies a tracer stem 100 which is slidably mounted in a vertically disposed tubular hub or sleeve member 101 formed, in this instance, integral with tracer arm 94 at the outer end thereof. Tracer stem 100 has a plunger head 102 at the upper end thereof forming an operating button there-

for. A coil spring 103 is mounted around the upper end of stem 100 under compression between a shoulder provided by housing 101 and the under side of button 102, so that, the tracer stem is normally biased to raised position out of tracing or scanning engagement with a pattern on the master wheel M therebelow. At its lower end tracer stem 100 removably mounts a stylus 104 depending therefrom for tracing engagement with a pattern on master wheel M, when the tracer stem is depressed. Tracer stem 100 also mounts at its lower end a cap member providing an upwardly extending annular flange 105 therearound which slidably extends up over and around the exterior of housing 101 and provides a camming surface for a purpose to be hereinafter described.

The indexable master unit is constituted by a master wheel M having a laterally forwardly projected annular flange 110 therearound providing a peripheral surface 111 for receiving and removably mounting thereon a series of patterns 112 (see Fig. 1). These patterns 112, in the present example, are individually removable and replaceable on the surface 111, which surface may be suitably formed to provide seats or bases spaced therearound for mounting the patterns.

The master wheel M, referring now to Fig. 19 in connection with Fig. 5, is rotatably mounted 20 in vertically disposed position at the forward side of arm structure 15 for rotation about a horizontal axis disposed transversely of the machine, in position with the highest portion of the upper side of rim 110 located directly below the tracer 25 unit A at the outer end of tracer arm 94. The rotatable mounting for pattern wheel M embodies, a spindle 114 journaled in antifriction bearing assemblies 114a carried in a hub portion 15a at the forward end of arm structure 15. The hub portion 110a of master wheel M is secured 30 to the forward end of spindle 114 by a suitable securing bolt or the like member 110b. A circular shield is mounted on the hub 15a and provides a forwardly extended flange 115a spaced outwardly from and around and concentric with the pattern mounting flange 110 of wheel M, with this flange 115a cut away at the upper side thereof to form a tracing station at which a selected pattern 112 is positioned and exposed for tracing engagement by tracing style 104 of the tracing unit A. In the instant example, pattern wheel M is manually rotatable in either direction to position a selected pattern 112 at the tracing station at the upper high side of the wheel M.

An indexing mechanism is provided for releasably locking master wheel M in position with a selected pattern at the tracing station. The master wheel M at the rear side thereof is provided with a spaced series of indexing notches N 55 therearound extending radially inwardly from the periphery of the wheel (see Figs. 2, 5 and 19), with each of the notches N lying in a radial plane which passes through the center of a pattern mounting base on the surface 111 of wheel M. A supporting housing structure 116 is secured at the upper side of hub 15a of arm structure 15 on the rear of shield 115 and this housing structure mounts a horizontally disposed casing 117 within which there is slidably mounted an indexing plunger 118. Plunger 118 projects forwardly from casing 117 in position for engaging and seating at its forward end into an indexing notch N of wheel M. Indexing plunger 118 is spring biased by a spring 118a to forwardly projected, index notch engaging position.

Plunger 118 is retractable against the force of biasing spring 118a to a position with its forward end withdrawn clear of wheel M and of the indexing notches N therein for free rotation of the master wheel to index a desired pattern 112 on the wheel to the tracing station. In this instance the indexing plunger 118 is maintained against rotation in casing 117 by a set screw 118b which is slidably received at its inner end in a longitudinally disposed slot 118c formed in the plunger.

Plunger 118 is provided with a rearwardly extending stem 119 which projects slidably and outwardly through the rear end of casing 117. Retraction of the indexing plunger 118 is effected by means of a flexible line 120 which is connected to the rear end of stem 119 and extends over an idler pulley 120a, and downwardly therefrom to the upper end of a pivoted foot pedal 121 mounted in position accessible to the foot of an operator, as will be clear by reference to Figs. 1 and 3. Thus, by rocking pedal 121 downwardly the operator pulls flexible line 120 downwardly and draws plunger 118 rearwardly to retracted position releasing master wheel M for indexing. Upon release of foot pedal 121, biasing spring 118a acts to return the plunger 118 to projected position for engaging into an indexing notch N positioned therewith to lock the master wheel in an indexed position.

The indexing plunger 118 is releasably locked in projected position against retraction, by a locking bolt 122. This bolt 122 is mounted in vertically disposed position for reciprocation in a casting 122a carried by housing structure 116, and is biased to upwardly projected, locking position by a biasing spring 122b. The stem 119 of plunger 118 is provided with a depending, radially disposed latch block 123 positioned in line between casing 117 and bolt 122 when the latter is in upwardly projected position, so that, latch block 123 engages bolt 122 and prevents retraction of the indexing plunger 118 by retracting forces applied to stem 119. Bolt 122 is retractable downwardly to position clear of latch block 123 so that the indexing plunger 118 may then be retracted rearwardly to position clear of and releasing the master wheel M for indexing rotation.

The locking bolt 122 is retracted against the forces of the biasing spring 122b, by means of a solenoid 124 which is mounted in position with its armature 124a extended vertically upwardly therefrom and pivotally coupled at its upper end with the lower end of bolt 122. Energization of solenoid 124 draws its armature 124a downwardly to thereby retract locking bolt 122. The energization of the solenoid 124 releases lock bolt 122 and biasing spring 122b then acts to project the bolt upwardly to position locking indexing plunger 118 against retraction.

Work piece indexing mechanism

The work piece holding and indexing mechanism B, referring now to Figs. 2, 5, 12 and 14 in connection with Fig. 1, includes a mounting base bar 125 which is removably attached on the universally laterally movable work table 80 in position disposed longitudinally of and across the table (see Fig. 5). The base bar 125 mounts spaced apart thereon, a series of vertically disposed posts 126, each of which provides at its upper end a horizontal journal box or bearing housing 126a disposed transversely of the mounting bar and within which there is journaled a work piece mounting and indexing spindle or

arbor 127. The spindles 127 are arranged in parallelism and disposed horizontally with their axes parallel with the straight line path of transverse or "in" and "out" movements of work table 80 relative to the machine.

Each work mounting spindle 127 is formed at its forward end to mount a work piece W thereon for indexing rotation thereby, there being in this instance four (4) work piece mounting spindles for mounting work pieces W for working engagement by the cutters C of the four (4) motorized spindle units S. Each work piece W may be removably mounted on the forward end of a spindle 127 by means of nuts or the like 128 (see Fig. 1) threaded onto the forward end of the spindle, the work pieces each being provided with a bore therethrough for receiving therein the work mounting end of a spindle.

In the illustrated example, the work pieces W are in the form of circular numbering discs which are to have engraved on and around the peripheral edges thereof, various numbers, letters, symbols, or other designs by the cutter spindles C. Hence, the work mounting spindles 127 are so positioned that with the work pieces W mounted thereon, these work pieces lie with their peripheries below and aligned with cutters C for working engagement of the cutters with the peripheral portions of the work pieces directly therebelow.

The work piece mounting spindles 127 are freely rotatably journaled in the journal boxes 126a, and each extends rearwardly a distance from the rear end of its journal box. On the rearwardly projected end, each work piece indexing spindle 127 has mounted thereon for rotation therewith an indexing wheel 130 provided around the periphery thereof with a series of radially disposed teeth forming therebetween the series of indexing notches 131. The number of indexing notches 131 on each indexing wheel 130 corresponds to the number of designs to be engraved around the periphery of a work piece W through 360° of rotation of the indexing wheel, spindle 127 and a work piece W mounted thereon. A work piece W is mounted and positioned on an indexing spindle 127, so that for each indexing position of the wheel, that portion of the periphery of the work piece to be engraved will be positioned below the cutter C of a spindle unit S thereabove.

The indexing wheels 130 are rotated step by step through their consecutive work indexing positions by the air cylinder and piston unit D which is mounted at one end, in this instance the left hand end, of mounting bar 125, as a component of the indexing mechanism assembly. An indexing bar or rod 132 is reciprocally mounted in horizontal position disposed longitudinally across base 125, above and across the rear ends of the indexing spindles 127 immediately adjacent the rear sides of the indexing wheels 130. This reciprocal indexing bar is slidably mounted at its opposite ends in upstanding support structures at opposite ends of the base bar 125, and is actuated from the air cylinder and piston unit D.

The air cylinder unit D, referring to Fig. 2, includes the cylinder 133 with the piston 133a and piston rod 133b reciprocally mounted therein. The piston rod 133b extends outwardly from the inner end of the cylinder 133. Air cylinder unit D is positioned with the axis of piston rod 133b thereof aligned with the axis of indexing bar

132, and the adjacent ends of the piston rod and bar are connected by an adjustable coupling 134. Thus, reciprocation of piston rod 133b by piston 133a in the cylinder 133 will reciprocate the indexing bar 132 along a straight line, horizontal path to the right and to the left, that is, longitudinally of the machine. The piston 133a of air cylinder unit D is air pressure operated in both directions through the medium of the air lines 135 and 136 which are connected and open into cylinder 133 at opposite sides of the piston. These air lines 135 and 136 each function to alternately supply air under pressure to and to exhaust air from that end of cylinder 133 with which it is connected, and are controlled or alternately set up by the solenoid actuated control valve unit F.

Indexing pawls 137 are pivotally mounted on the forward side of indexing rod 132 for indexing engagement with the indexing wheels 130, respectively. Each indexing pawl 137, in this example, extends in a direction to the left from its pivot and is provided with a depending tooth 137a which in normal indexing position of bar 132 is engaged in that indexing notch 131 of an indexing wheel which is positioned on the plane of the vertical diameter of the wheel (see Fig. 12). These indexing pawls 137 are spring biased downwardly by springs 137b, and upon the indexing stroke of bar 132 to the right, are swung upwardly by the advancing tooth of the wheel and ride out of the notch in which engaged, over the advancing tooth, and snap down into the next indexing notch 131 of the indexing wheel.

A locator pawl 138 is provided for each indexing wheel 130 for the purpose of locating the final position of the indexing, as well as for locking the indexing wheel 130, with spindle 127 and work piece W thereon, in indexed position until the next indexing cycle. In this example, each locator pawl 138 is mounted on and carried by an arm 138a pivotally mounted at its lower end by a pivot pin 138b, and extends vertically upwardly therefrom along the right hand sides of the adjacent index wheel and indexing pawl with which it is functionally associated. Each locator pawl 138 is connected at its upper end to the end of a coiled contractile spring 139 which extends therefrom to the left above the adjacent indexing pawl 137, and to a fixed point on the indexing bar 132 at which the spring is connected. Spring 139, when the indexing bar 132 is in normal position moved to the left, biases the arm 138a with which it is connected into position engaging the locator pawl 138 in that index notch 131 of wheel 130 aligned with the pawl to thus lock the wheel in the desired indexed position against rotation.

Each locator pawl carrying arm 138a is in position to be engaged by the adjacent indexing pawl 137 on rod 132 when that rod is moved to the right on its pawl setting stroke, preparatory to its indexing stroke to the left. Thus on the stroke of rod 132 to the right arm 138a are engaged by the pawls 137, respectively, and the arms 138a are simultaneously rocked to the right against the biasing forces of springs 139, so that, the locator pawls 138 are simultaneously moved and cleared from engagement in the indexing wheel notches. On the pawl setting stroke to the right, the indexing pawls ride over into the next indexing notches 131 of the indexing wheels 130. Then when indexing rod 132 is moved to the left on its indexing stroke, the indexing pawls 137 rotate the indexing wheels 130 simultaneously and in precise synchronism, to the next

position of index. Such indexing rotation of the wheels 130 takes place in advance of the swinging of arms 138a to the left under the action of springs 139, so that, upon completion of the indexing rotation of wheels 130 to the indexed position, the locator pawls 138 then move into engagement in the indexing notches 131 of the wheels which are respectively aligned with the locator pawls. In this manner, the indexing wheels and the work pieces W are secured and locked in indexed position until the next indexing cycle. In Fig. 12 of the drawings, the work piece indexing mechanism is shown in indexed position with the indexing bar 132 in its position at the limit of its indexing stroke to the left and with the locator pawls 138 locking the index wheels in the position of index.

Air line and control valve system

20 The air cylinder and piston units D and E, for operating, respectively, the work piece indexing mechanism B and the spindle unit feed mechanism, are supplied with air under pressure from any suitable source external to the machine (not shown) by the air supply line 150 shown in Figs. 2 and 20.

25 The air cylinder unit D is controlled by a control valve unit F of the solenoid actuated type which is supplied at its intake side with air under pressure by the branch line 151 from the air supply line 150. The operating side of valve unit F is connected with the air lines 135 and 136 which extend to and are connected with air cylinder 133 of unit D at opposite sides of the piston 133a therein. The control valve unit F may be of any of the well-known, so-called three-way types familiar in the art and it is deemed unnecessary to make herein a detailed disclosure thereof. Such a unit includes an arrangement of ports therein controlled by a valve stem or plunger unit FV operable to set up the valve unit in one position of the stem unit for discharge of air under pressure through line 135 to air cylinder 133, while connecting air line 136 to an exhaust 152 to atmosphere; and in the opposite or reverse position of the valve stem unit FV to set up the valve unit to connect line 136 with air under pressure and connect line 135 with an exhaust 153 to atmosphere.

30 35 40 45 50 55 60 65 70 Valve unit F includes solenoid unit FS for actuating when energized, the valve stem unit FV to position setting up line 135 for supplying air under pressure to the outer end of cylinder 133, while exhausting the cylinder through line 136 to move indexing rod 132 to the right on its indexing pawl setting-up stroke. The solenoid of valve unit F may be spring loaded so as to restore the opposite setting of the valve unit when de-energized, to thereby effect supply of air under pressure to line 136 to the inner end of cylinder 133, while exhausting through line 135, to thus force piston 133a outwardly for an indexing stroke of indexing rod 132 to the left.

75 The operation of the air cylinder and piston E 65 for actuating the cutter spindle unit feed mechanism, is controlled by the air valve unit G which latter unit is supplied with air under pressure by an air line 154 which may be branched from the main air line 150. The inner end of cylinder 50 of unit E is connected with the control valve unit G by a pressure supply-exhaust line 58. Control valve unit G may be of any of the well-known, two-way types, hence a detailed disclosure thereof is not considered necessary herein. Such unit includes an actuating solenoid GS and

a valve plunger or stem unit GV, together with an arrangement of ports controlled by the stem in such a manner that in one position of stem unit GV the valve supplies air under pressure to cylinder 50 through line 58, while in the opposite or reverse position thereof, line 58 is cut off from the pressure supply and is opened to an exhaust line 155 of the valve unit to atmosphere. When solenoid GS is energized, valve stem unit GV is positioned thereby to open line 58 for discharge of air under pressure therethrough to cylinder 50 to effect feed of the cutter spindle units S downwardly to working positions. The solenoid unit GS may be spring loaded, so that, upon de-energization thereof the valve stem unit GV is restored to position setting up the valve unit to cut off line 58 from the air supply and to open this line for release of pressure and exhaust to atmosphere through exhaust 155. The biasing spring 55 of unit E may then force piston 51 downwardly and rearwardly to effect operation of the spindle unit feed mechanism to raise spindle units S from working positions.

Electrical control circuit and interlock switch system

The solenoids FS and GS of the control valve units F and G, respectively, and the solenoid 124 for the locking bolt 122 for indexing plunger 118, are supplied with electrical current from a suitable source (not shown) external to the machine, by the machine mounted supply lines 200 and 201 shown in Fig. 20.

Referring to Fig. 20, the circuit through solenoid GS comprises the circuit line 202 connected between supply line 200 and the input side of the solenoid GS; the normally closed switch 140 in line 202; the circuit line 203 from the output side of solenoid GS back to supply line 201; the normally closed switch 141 in circuit line 203; and the normally open switch 142 in circuit line 203 between switch 141 and the supply line 201.

The switch 140 in line 202 may be of the well-known microswitch type and, referring now to Fig. 19, is mounted within housing 116 with its actuating plunger 140a extended vertically upwardly through aligned openings in the upper wall of the housing and the adjacent lower wall of casing 117, into position for camming engagement at its upper end by the inner end of indexing plunger 118 when that plunger is drawn rearwardly to position releasing master wheel M for indexing rotation. Switch 140 is restored to and remains in normally closed position when the indexing plunger 118 is in its forwardly projected, master wheel locking position, clear of camming engagement with switch actuating pin 140a.

Interlock switch 141 is also of the microswitch type and is mounted as a component of the work piece indexing mechanism assembly B. Referring now to Figs. 2 and 12, switch 141 is mounted on the base bar 125 and includes a spring actuating arm 141a at the upper side thereof for operating the switch actuating plunger 141b. Arm 141a mounts a roller at the free end thereof for camming engagement by a cam block 141c mounted in position fixed on and movable with indexing bar 132. Switch 141 is normally closed by engagement of the cam block 141c with the switch actuating arm 141a when the indexing bar 132 is in position at rest at the end of its indexing stroke to the left, as shown by Fig. 12. When bar 132 is moved to the right from position of index 132 to start an indexing stroke, cam block 141c is disengaged from switch closing, camming engage-

ment with the arm 141a, so that switch 141 is restored to open position, opening the circuit line 203.

Switch 142 may be of the microswitch type and, referring again to Fig. 19, is mounted in a suitable housing in the under side of tracer arm 94 of the pantograph P, immediately to the rear side of tracer hub 101. Switch 142 is normally open and includes a switch actuating plunger 142a which projects horizontally forwardly therefrom for camming engagement by a flange member 105 of the vertically reciprocal tracer stem 100. In raised, non-tracing position of tracer 100, flange 105 is in engagement with switch actuating plunger 142a and cams this plunger inwardly to circuit opening position of switch 142. Plunger 142a is spring loaded and upon movement of tracer 100 downwardly to position in tracing engagement with a pattern 112 on master wheel M, camming flange 105 is then lowered to position clear of the switch plunger, so that the plunger snaps outwardly to effect actuation of the switch to position closing the circuit therethrough.

Referring again to Fig. 20, the circuit through solenoid FS of the control valve unit F for air cylinder unit D, comprises a circuit line 204 connected between supply line 200 and the input side of solenoid FS; a normally open switch 143 in line 204; a circuit line 205 from the output side of solenoid FS; a circuit line 206 connected into line 205 and leading back to supply line 201; and a normally closed switch 144 in circuit line 206.

The switch 143 is, in this instance, of the microswitch type and is mounted in position at the under side of tracer arm 94 immediately to the rear of switch 142, as will be clear by reference to Fig. 19. Switch 143 is provided with an actuating plunger 143a which projects outwardly at the right hand side of tracer arm 94, as clearly shown in Fig. 3. Switch 143 is normally open and is adapted to be closed by manual depression of the plunger 143a by the operator of the machine to effect an indexing cycle of the work piece indexing mechanism B. The switch is of the spring loaded type, so that, when plunger 143a is released after depression, the switch restores to circuit opening position.

Interlock switch 144, referring now to Fig. 16 in particular, may be of the microswitch type and is mounted in position adjacent the upper side of air cylinder unit E of the spindle feed actuating mechanism. Switch 144 includes at the inner side thereof, a switch actuating plunger 144a which is adapted to be depressed by a switch operating arm 144b, which arm extends across the switch and mounts at its forward free end a contact roller. The collar 59 on piston rod 52 of cylinder unit E has fixed thereon a radially dis-

posed upwardly extended contact pin 144c which is positioned in line with the contact roller at the end of switch arm 144b, so that, upon downward and rearward movement of collar 59 with rod 52, the contact pin 144c will engage the roller on switch arm 144b and thereby actuate the switch to circuit closing position. When piston rod 52 is in forwardly projected position of downward feed of spindle units S, contact pin 144c is disengaged from switch arm 144b and the switch actuating pin 144a, which may be spring loaded, moves to circuit opening position of the switch 144.

The circuit through solenoid 124 which controls the locking bolt 122 for the indexing plunger 118 (see Fig. 19), comprises the circuit line 207

from circuit line 202 and the supply line 200, to the input side of solenoid 124; the circuit line 208 from the output side of solenoid 124 to the circuit line 206, through the switch 144 and the circuit line 206, back to supply line 201. Thus, solenoid 124 is energized when switch 144 is closed and is de-energized by the opening of switch 144.

General operation

With the machine inactive and at rest, the cylinder unit E of the spindle feed mechanism has the plunger 52 thereof in retracted position under the action of spring 55, with the cutter spindle units S in their raised positions and the cutters C raised from cutting engagement with the work pieces W on the work holding mechanism B. This position of the foregoing mechanisms is maintained because the circuit through air control valve unit G for the air cylinder unit E, is open with its solenoid GS de-energized, due to the fact that switch 142 is maintained in open position by the raised, inactive position of tracer stem 100 with the camming flange 105 thereof in switch opening engagement with switch actuating pin 142a. With solenoid GS de-energized, the control valve unit G is actuated to position cutting off supply of air under pressure to the cylinder unit E and opening that unit to atmosphere, so that, spring 55 retracts plunger 59 and spindle units S are fed upwardly to raised positions.

The circuit through solenoid FS of air control valve unit F for the air cylinder unit D of the work piece indexing mechanism B, is open with the solenoid de-energized, due to the fact that the indexing control switch 143 is open, while the switch 144 controlled by the spindle feed mechanism is closed by the engagement of contact pin 144c with switch arm 144b. With solenoid FS de-energized, control valve unit F is in position for supplying air under pressure to the inner end of cylinder unit D through air line 136, and the indexing bar is at the end of its indexing stroke to the left with the indexing mechanism in a position of index.

The locking bolt 122 for the master wheel indexing plunger 118 with the machine in inactive position, is retracted by the solenoid 124 to unlocked position, as the circuit therethrough is closed, due to the fact that the switch 144 in this solenoid circuit is closed by the inactive position of cylinder unit E of the cutter spindle unit feed mechanism. Thus, the master wheel indexing plunger may be retracted by operation of foot pedal 121 to unlock the master wheel M for indexing a pattern 112 to the tracing station below tracing stylus 104 of tracing stem 100.

To operate the machine to perform an engraving operation, the operator first retracts indexing plunger 118 to position releasing master wheel M and then rotates this wheel manually to position a desired pattern 112 at the tracing station.

The indexing plunger 118 is then released and projects into the indexing notch N of the wheel M for the particular pattern 112 thereon which has been indexed to the tracing station.

It is to be noted that during the operation of indexing the master wheel M, the interlock switch 140 is operated to open position by the retraction of the indexing plunger 118. The opening of interlock switch 140 opens the circuit through solenoid GS of air control valve unit G, so that, it is impossible for the operator to effect a down feed of the cutter spindle units S,

even if the operator, by operation of tracer stem 100, should close the switch 142 in the circuit to solenoid GS.

Thus, an effective and fool-proof interlock system is provided which prevents down or working feed of the cutter spindle units S and cutters C mounted therein, into working engagement with work pieces W during the indexing of the master wheel M.

After the desired pattern 112 on master wheel M has been indexed to the tracing station, the operation of engraving simultaneously a scaled reproduction of the selected pattern on the work pieces W may be effected. To do so, the operator depresses tracer stem 100 downwardly to engage the stylus 104 in tracing contact with the pattern 112 at the tracing station. Depression of tracer stem 100 to tracing position closes switch 142, which in turn closes the circuit through and energizes solenoid GS of the control valve unit G for cylinder unit E. This actuates control valve unit G to position supplying air under pressure through line 58 to cylinder unit E to thereby effect projection of the piston rod 52 of the unit, forwardly and cause feed of the cutter spindle units S downwardly to engage the cutters C mounted therein with the work pieces W. This down feed of the cutter spindle units S is thus effected simultaneously with and by the engagement of the tracing stylus 104 with a pattern. The operator then scans the pattern 112 with the tracing stylus 104, and the pantograph mechanism P functions to transmit such tracing movements to the sensitive table 80 in scaled reproduction, to thereby move table 80 with work pieces W thereon relative to the cutters C, so that, the cutters reproduce in scaled reduction, accurately and with precision on the work pieces W, the profile of the pattern.

Immediately upon release by the operator of the tracer stem 100, that stem is raised by its biasing spring 103 to position out of tracing engagement with pattern 112, and the camming flange 105 actuates switch 142 to open position.

Thus the circuit through solenoid GS of valve unit G is opened, and this valve unit restores to position cutting off supply of air under pressure to cylinder unit E and opening that unit for pressure release and discharge to atmosphere. Spring 55 of unit E then acts to retract piston rod 52 and thereby operate the feeding mechanism to raise simultaneously the cutter spindle units S and cutters C to positions clear of and out of cutting engagement with the work pieces W. By the functioning of the interlock switch 142 under the control of the tracer stem 100, the cutter spindle units S can only be fed downwardly to working positions by the movement of the tracer stem 100 into tracing engagement with a pattern, the feeding of the spindle units downwardly being effected by and simultaneously with the depression of the tracer stem to position engaging stylus 104 with a pattern. Conversely, whenever tracer stem 100 is permitted to rise to disengage stylus 104 from tracing engagement with a pattern, the cutter spindle units S are automatically, simultaneously fed upwardly to positions with cutters C thereof out of work engagement with the work pieces W.

When an engraving operation from an indexed pattern has been completed and the tracer 100 is in raised position with resulting up-feed simultaneously to raised positions of cutter spindle units S, the operator may then index master wheel M to position another pattern 112 at the

tracing station, or may repeat an engraving operation from the same pattern. But in either event, before the next engraving operation, the work pieces W are indexed simultaneously by the indexing mechanism B to present the next portions of the peripheries thereof to be engraved. Work piece indexing is effected by the operator depressing plunger 143a (see Fig. 3) of switch 143 located on the tracer arm 94, to thus position that switch to close the circuit through solenoid 10 FS of the air control valve unit F of cylinder unit D. Closing of switch 143 with energization of solenoid FS effects operation of valve unit F to a position at which air under pressure is admitted through line 135 to the outer end of cylinder unit D, while the inner end thereof is open to exhaust to atmosphere through line 136. This results in moving indexing bar 132 to the right on an indexing pawl setting stroke. The operator then releases switch plunger 143a and switch 20 143 restores to open position. This deenergizes solenoid FS, and valve unit F then restores to position supplying air under pressure to the inner end of cylinder unit D through line 136, line 135 being opened to atmosphere. Indexing plunger 132 is then moved to the left on its indexing stroke and the work pieces W are rotated simultaneously to position the next portions of their peripheries in indexed position vertically aligned with the cutter spindles C. After which the engraving operation may be performed in the manner as above described.

On the indexing stroke of indexing bar 132, the interlock switch 141 in the circuit through solenoid GS of the feed mechanism control valve unit G, is opened. Thus, it becomes impossible to inadvertently effect a down feed of the cutter spindle units S, even if the operator should depress tracer 100 and close switch 142 in that circuit. This effectively safeguards against any 40 possible engagement of the cutters C and the cutter spindle units S with the work pieces W during indexing of those pieces.

In the example machine hereof, an indexable master unit in the form of the master wheel M of the invention, is utilized, with this wheel mounted for rotation in a vertical plane about a horizontal axis disposed transversely relative to the machine. However, this indexable master wheel can, if desired or found expedient in the adaptation of the invention to other conditions or machines, be mounted for rotation in a horizontal plane about a vertical axis with the patterns mounted around the upper side of the wheel. Further, the invention contemplates the substitution for the wheel type of master unit of any other suitable type by which patterns may be selectively presented to the tracing station. And a machine organization of the invention is not necessarily limited to the use of an indexable pattern unit. In its broader aspects a tracing station may be provided at which various patterns may be individually removably mounted, the broad feature of this phase of the invention being constituted by the interlock control through the medium of which, when a pattern unit is being indexed or patterns are being changed at the tracing station, the cutter spindle feed mechanism is rendered inoperative, while the work piece indexing mechanism is rendered 70 operative.

A machine embodying the broad combinations of the invention is not limited or restricted to multiple spindles and/or to multiple work pieces, as, if desired, a single spindle machine may be

provided within the broad combination of the invention which includes the interlocked tracer and cutter spindle feed with or without the combination of the invention which includes the interlock between the work piece indexing mechanism and the pattern indexing. Further, a machine organization of the invention is not limited to the use of a motorized spindle unit, but may also utilize conventional spindles of various types mounted for feeding to and from working positions.

While in the preferred form of the example machine, the spindle unit feed actuating means and the actuating means for the work piece indexing mechanism, are of the pneumatically operated types, the invention is not limited or restricted to such types, as hydraulically actuated types may be utilized if it is desired or found expedient.

It will also be evident that various other forms, designs, adaptations, modifications, substitutions, additions, eliminations, combinations and subcombinations may be resorted to without departing from the broad spirit and scope of the invention and to the various features thereof to the exact and specific expressions of the example machine organization, except as may be required by specifically intended limitations thereto appearing in the appended claims.

What I claim is:

1. In combination, a work table and a cutter spindle mounted for relative movements; said cutter spindle being also mounted for movements to and from working and non-working positions relative to said table; pressure fluid actuated means for moving said cutter spindle from non-working to working position; an electrically operated pressure fluid control valve for said actuating unit, including an operating circuit therefor, and a normally open control switch in said circuit; a tracer mounted for tracing movements over a pattern and being also mounted for movements to and from pattern engaging and disengaging positions; mechanism connected with said tracer for effecting relative movements between said table and cutter spindle in scaled relation with the movements of said tracer over a pattern; and means operated by said tracer for opening said control switch when the tracer is in pattern disengaging position and for closing said switch when the tracer is in pattern engaging position.

2. In the combination as defined in claim 1, biasing means acting to continuously bias the cutter spindle feed mechanism and actuating means to non-working position of the cutter spindle, and biasing means acting to continuously bias the tracer to pattern disengaging position.

3. In combination, a work table and a cutter spindle mounted for relative movements; said cutter spindle being also mounted for movements to and from working and non-working positions relative to said table; pressure fluid actuated means for moving said cutter spindle from non-working to working position; an electrically operated pressure fluid control valve for said actuating means including, an electrical operating circuit therefor, and a normally closed control switch in said circuit; a tracer mounted for tracing movements over a pattern; mechanism connected with said tracer for effecting relative movements between said table and cutter spindle; a master unit mounted for indexing relative to said tracer; mechanism operable to releasably

lock said master unit in an indexed position; and means operated by operation of said master unit locking mechanism to release said unit for opening said control switch in said pressure fluid control valve operating circuit.

4. In the combination as defined in claim 3, said master unit locking mechanism including an indexing plunger for releasably locking said master unit in an indexed position, and said normally closed control switch being adapted to be opened by operation of said plunger to release the master unit for indexing.

5. In combination, a work table and a cutter spindle mounted for relative movements, said cutter spindle being also mounted for movements to and from working and non-working positions relative to said table; pressure fluid actuated means for moving said cutter spindle from non-working to working positions; and an electrically operated pressure fluid control valve for said actuating means including, an electrical operating circuit for said valve, and a normally closed control switch in said circuit; a tracer mounted for tracing movements over a pattern; mechanism connected with said tracer for effecting relative movements between said table and cutter spindle by tracing movements of said tracer; work piece indexing mechanism on said table for indexing a work piece relative to said cutter spindle; and means actuated by indexing operation of said work indexing mechanism for opening said normally closed control switch in the control circuit to said valve unit.

6. In the combination as defined in claim 5, a pressure fluid operated unit for actuating said work piece indexing mechanism, and an operator control for said pressure fluid operated unit.

7. In the combination as defined in claim 5, a pressure fluid actuated unit for operating said work indexing mechanism; an electrically operated pressure fluid control valve for said pressure fluid operated unit, including an electrical control circuit; and a control switch in said control circuit adapted to be selectively operated by an operator to control the operation of said unit.

8. In combination, a work table and a cutter spindle mounted for relative movements; said cutter spindle being also mounted for movements to and from working and non-working positions relative to said table; pressure fluid actuated means for moving said cutter spindle from non-working to working position; and an electrically operated pressure fluid control valve unit for said actuating means, including, an electrical circuit for said valve unit for setting said valve unit when closed to effect movement of said spindle to working position, and a normally closed switch in said circuit; a tracer mounted for tracing movements over a pattern; mechanism connected with said tracer for effecting relative movements of said table and spindle by tracing movements of the tracer; a master unit mounted for indexing relative to said tracer; an indexing plunger mounted for movements to and from position locking said master unit in indexed position; said indexing plunger being adapted when moved from locking position to open said normally closed control switch; a locking member movable to and from positions locking and unlocking said indexing plunger; an electrically operated unit for moving said locking member to unlocked position, including a control circuit, and a normally closed switch therein; and means actuated by movement of said cutter spindle to working position for

opening said normally closed switch in the circuit of said locking member moving unit.

9. In the combination as defined by claim 8, the electrically operated unit for the locking member comprising a solenoid spring loaded to continuously bias said unit to move said locking member to unlocked position, an electrical control circuit for energizing said solenoid to effect movement of said locking member to unlocked position, and a normally open, manually operable control switch in said control circuit.

10. In combination; a work table and cutter spindle mounted for relative movements; mechanism for feeding said cutter spindle between working and non-working positions relative to said work table; powered actuating means for operating said feed mechanism to feed said cutter spindle between working and non-working positions, said actuating means comprising a pressure fluid cylinder and piston unit adapted to be operated by fluid pressure in one direction to operate the feed mechanism, to feed the spindle to working position, and a biasing spring adapted to actuate said unit in the reverse direction to operate said feed mechanism to feed the cutter spindle to non-working position; a tracer mounted for tracing movements over a pattern, said tracer being also mounted for movements between pattern engaging and disengaging positions and including, biasing means continuously urging said tracer to pattern disengaging position, said tracer being adapted to manually actuated against its biasing means to and held in pattern engaging position; and means operatively associated with said tracer and with the actuating means for said spindle feed mechanism adapted to effect fluid pressure operation of said actuating means simultaneously with the movements of said tracer to pattern engaging position to thereby feed said spindle to working position.

11. In a machine tool organization, in combination, a frame structure; a work table mounted on said structure for universal lateral movements; said work table being also mounted for movements bodily transversely of the plane of lateral swing to adjusted positions on said structure; a cutter spindle mounted on said frame structure in fixed position laterally; a pantograph linkage pivotally supported from said frame structure independently and in position at one side of said work table for universal lateral movements in a plane generally parallel with the plane of lateral movements of the table, said pantograph linkage being supported in fixed position relative to said frame structure against movements transversely relative to said plane of lateral swing; a tracer connected with said pantograph linkage for tracing movements over a pattern; and coupling mechanism between and being pivotally connected to said pantograph linkage and said work table, respectively, on axes parallel with the planes of lateral movement of said table and linkage for adjustment of said table transversely of said planes and independently of the linkage.

12. In the combination of claim 11, said coupling mechanism having means for adjusting said work table in either direction laterally independently of and relative to said linkage along a path generally parallel with the pivot axis of the connection between the table and said coupling mechanism.

13. In combination; a work table and a cutter spindle mounted for relative movements therebetween; work piece mounting and indexing

31

mechanism mounted on said work table; a cutter spindle mounted for feeding movements between a working position and a non-working position relative to said work piece mounting and indexing mechanism; feed mechanism for feeding said cutter spindle between working and non-working positions; a tracer mounted for tracing movements over a pattern and being also mounted for movements between a pattern engaging position and a pattern disengaging position; movement transmitting mechanism connected with and adapted to be actuated by said tracer for transmitting movements of the tracer into relative movements between said cutter spindle and said work table in scaled reproduction of the movements of said tracer; tracer controlled interlock means connected with said tracer and with said spindle feed mechanism adapted to be operated by movements of said tracer from pattern engaging position to pattern disengaging position to render said spindle feed mechanism inactive for feeding said spindle from non-working position to working position when the tracer is in pattern disengaging position; and work indexing mechanism controlled interlock means connected with said work indexing mechanism on said work table and with said tracer and being adapted to be operated by indexing actuation of said work mounting and indexing mechanism to render said feed mechanism inactive for feeding said spindle from non-working to working position during work piece indexing.

14. In combination, a work table and a cutter spindle mounted for relative movements therebetween; a work piece mounting and indexing mechanism on said work table; a cutter spindle mounted for feeding movements between a working position and a non-working position relative to said work piece mounting and indexing mechanism; feed mechanism connected with said cutter spindle for feeding said spindle between working and non-working positions; a tracer mounted for tracing movements over a pattern and being also mounted for movements between a pattern engaging position and pattern disengaging position; movement transmitting mechanism connected with and adapted to be actuated by said tracer for relatively moving said work table and cutter spindle in scaled reproduction of the tracing movements of said tracer; tracer controlled interlock means connected with said tracer and with said spindle feed mechanism and being operable by movements of said tracer between pattern engaging and pattern disengaging positions to effect the simultaneous operation of said feed mechanism to feed said cutter spindle from non-working position to working position and from working position to non-working position, respectively; and a work indexing mechanism controlled interlock connecting said work indexing mechanism with said tracer controlled interlock means and being adapted to render said latter interlock means inoperative to cause an operation of said feed mechanism to feed said spindle from non-working to working position during indexing operation of said work piece mounting and indexing mechanism.

15. In combination; a work table and a cutter spindle mounted for relative movements therebetween; work piece mounting and indexing mechanism on said work table; a cutter spindle mounted for feeding movements between a working position and a non-working position relative to said work mounting and indexing mechanism; feed mechanism connected with said cutter spin-

32

dle for feeding said spindle between working and non-working positions; a tracer mounted for tracing movements over a pattern and being also mounted for movements between a pattern engaging position and a pattern disengaging position; movement transmitting mechanism connected with and adapted to be actuated by said tracer for relatively moving said work table and cutter spindle in scaled reproduction of the movements of said tracer over a pattern; an indexable master unit adapted to mount thereon the patterns to be traced by said tracer; locking mechanism operable to releasably lock said master unit in an indexed position; tracer controlled interlock means connecting said tracer and said spindle feed mechanism and being adapted for operation to render said spindle feed mechanism inactive to feed said cutter spindle from non-working position to working position by movements of said tracer from pattern engaging to pattern disengaging position; locking mechanism controlled interlock means connecting said locking mechanism for said master unit with said feed mechanism and being operable to render said feed mechanism inactive to feed said cutter spindle to working position by actuation of said locking mechanism to release said master unit for indexing; and work piece indexing mechanism controlled interlock means connecting said spindle feed mechanism with said work piece mounting and indexing mechanism to render said spindle feed mechanism inactive for feeding said cutter spindle to working position during work piece indexing by said indexing mechanism.

16. In combination; a work table and a cutter spindle mounted for relative movements therebetween; a tracer mounted for tracing movements over a pattern; mechanism connected with and actuated by said tracer for relatively moving said work table and cutter spindle in scaled reproduction of the movements of said tracer over a pattern; feed mechanism for feeding said cutter spindle between a working position and a non-working position relative to said work table; a pattern mounting master unit operable for indexing a pattern relative to said tracer; and interlock means connecting said master unit with said spindle feed and being adapted to be operated by indexing actuation of said master unit to render said feed mechanism inactive to feed said cutter spindle from a non-working position to a working position during indexing actuation of said master unit.

17. In combination; a work table and a cutter spindle mounted for relative movements therebetween; a spindle feed mechanism for feeding said cutter spindle between non-working and working positions; work piece mounting and indexing mechanism on said work table; a tracer mounted for tracing movements over a pattern; movement transmitting mechanism connected and adapted to be actuated by tracing movements of said tracer over a pattern to effect relative movements of said table and spindle in scaled reproduction of the movements of said tracer; and interlock means connected with said work indexing mechanism and with said spindle feed mechanism and being adapted to be operated by indexing operation of said work indexing means to render said spindle feed mechanism inactive to feed said cutter spindle from a non-working position to a working position during indexing operation of the said indexing mechanism.

18. In combination; a work table and a cutter spindle mounted for relative movements therebetween; work mounting and indexing mechanism on said table; a tracer mounted for tracing movements over a pattern and being also mounted for movements between pattern engaging and pattern disengaging positions; mechanism connected with said tracer for effecting relative movements of said table and spindle in scaled reproduction of the tracing movements of the tracer; mechanism for feeding said cutter spindle between working position and non-working position relative to said table; means operatively associated with said tracer and said spindle feed mechanism for effecting operation of said feed mechanism to feed said spindle between working and non-working positions simultaneously with movements of said tracer between pattern engaging and pattern disengaging positions, respectively; a master unit mounted for indexing relative to said tracer; mechanism operable to lock said master unit in a position of index and to release said unit for indexing; and a system of interlocks comprising, interlock means operatively associated with said work indexing mechanism and with said feed mechanism adapted to be controlled by indexing operation of said work indexing mechanism to render said feed mechanism inactive for operation to feed said cutter spindle during work indexing operation of said work indexing mechanism, interlock means operatively associated with said master unit locking mechanism and with said spindle feed mechanism adapted to be operated by an actuation of said locking mechanism to release said master unit to render said spindle feed mechanism inactive for operation during indexing of said master unit, and each of said interlock means being adapted to be operated upon completion of work indexing and of master unit indexing to render said spindle feed mechanism operable for spindle feeding.

19. In combination, a frame structure; a work table mounted on said structure for universal lateral movements; a cutter spindle mounted on said structure in fixed position against movements laterally thereon, said cutter spindle being also mounted on said structure for movements axially between a non-working position and a working position relative to said work table; a tracer supported from said frame structure and being mounted for universal lateral movements over a pattern and being also mounted for movements between a pattern engaging and a pattern disengaging position; movement transmitting mechanism connecting said tracer with said work table and being operable by tracing movements of said tracer to effect movements of said work table in scaled reproduction of said tracer movements; work piece mounting and indexing mechanism fixed on and movable as a unit with said universally laterally movable work table; said work piece mounting and indexing mechanism including actuating means therefor, and an operator control for said actuating means; and a tracer controlled interlock connecting said tracer and said operator control and being operable by movements of said tracer from pattern disengaging position to render said operator control inactive when said tracer is in pattern engaging position.

20. The combination as defined in claim 19, in which the actuating means for the work piece mounting and indexing mechanism is comprised by a pressure fluid actuated cylinder and piston

unit mounted on and movable as a unit with said universally laterally movable work table.

21. In the combination as defined in claim 19, the actuating means for the work piece mounting and indexing mechanism being comprised by a pressure fluid actuated unit mounted on and movable as a unit with said work table; said pressure fluid actuated unit including in operative connection therewith pressure fluid supply and exhaust lines leading therefrom, a pressure fluid control valve connected in said supply lines at a location removed from said universally laterally movable work table, and said operator control for the actuating means for the work piece mounting and indexing mechanism being operatively associated with said pressure fluid control valve.

22. In a machine tool organization, in combination; a fixed frame structure; a work table mounted on said frame structure; a plurality of cutter heads mounted on said frame structure with their axes substantially parallel and disposed generally normal to the plane of said work table; a cutter spindle unit mounted on each of said cutter heads for feeding movements axially therein to and from working and non-working positions relative to said work table; a feed mechanism common to and in continuous operative connection with all of said cutter spindle units in said cutter heads and being operable for feeding said units simultaneously to and from working and non-working positions; actuating means for operating said common feed mechanism for said spindle units; each of said cutter heads being slidably mounted on said frame structure for adjustment thereon laterally independently of each of said other cutter heads with said cutter spindle unit therein in constant operative connection with said common feed mechanism; and means for releasably locking each cutter head in a laterally adjusted position independently of each of the other of said cutter heads.

23. In the combination as defined by claim 22, said feed mechanism including a common shaft gear mounted on said frame structure; and a feed gear train mounted on and movable laterally as a unit with each of said cutter heads and being in constant feeding mesh with and slideable axially along said common shaft gear.

24. The combination as defined in claim 22, in which the actuating means for the common feed mechanism for the spindle units is comprised by a pressure fluid operated, double acting cylinder and piston unit, and in which stop means is provided by said cylinder and piston unit for limiting feed of said cutter spindles by said feed mechanism toward and from working and non-working positions.

25. The combination as defined in claim 22, in which each cutter spindle unit is provided with rack teeth and each cutter head mounts thereon a feed gear train including an inner gear in mesh with the cutter spindle unit rack teeth, and said inner gear is mounted for lateral displacement to position disengaged from the rack teeth of the spindle unit for removal of such unit from a cutter head independently of and without interrupting the operative driving connection of said other cutter spindle units with said feed mechanism.

26. In a machine tool organization, in combination; a frame structure; a support movably mounted on said frame structure for adjustment thereover in either direction along a

straight line path; a work table mounted on said support for universal lateral movements in a plane transverse to the path of adjustment of such support and being bodily movable as a unit with said support; a cutter spindle mounted on said frame structure in fixed position against movements laterally, said cutter spindle being mounted independently of said work table and said support and being also mounted for feeding movements axially to and from working and non-working positions relative to said table; a pantograph mechanism of the parallelogram-linkage type pivotally supported from said frame structure independently and in position at one side of said table for universal lateral movements in a plane generally parallel with the plane of lateral movements of said table, said pantograph mechanism being pivotally supported from said frame structure in fixed position against movements thereon transversely relative to the plane of the lateral movements thereof; a tracer connected with said pantograph mechanism for actuating said mechanism by tracing movements over a pattern; coupling means pivotally connecting said pantograph mechanism with said work table for transmitting to said table in scaled relation the movements of said tracer over a pattern; and said coupling means pivotally connected to said pantograph and to said table about parallel axes, disposed parallel, respectively, with the plane of movement of said pantograph mechanism and the plane of universal lateral movements of said work table.

27. In a machine tool organization, in combination; a column structure; a knee mounted on said column structure for adjustment bodily in either direction along a straight line path; a work table movably mounted on said knee for universal lateral movements thereon in a plane transverse to the path of knee adjustment and being bodily adjustable as a unit with said knee; a cutter spindle mounted on said column structure in position fixed against movements laterally thereon with its axis disposed generally normal to the plane of lateral movements of said work table; said cutter spindle being also mounted for feeding movements axially between working position and non-working position relative to said work table; a pantograph mechanism of the parallelogram-linkage type pivotally mounted on and supported from a fixed pivot on said column structure independently of said knee and work table; said pantograph mechanism being located

in position at and spaced from one end of said work table and being universally laterally swingable about and supported from said fixed pivot in a plane substantially parallel with the plane of lateral movement of said work table and being fixed against movements transversely of said plane of lateral movements; a tracer connected with said pantograph mechanism for universally laterally swinging the latter by movements of the tracer over a pattern; coupling means connecting the adjacent end of said work table and side of said pantograph mechanism in fixed lateral spacing therebetween for laterally transmitting to said work table in scaled relation the movements of said pantograph mechanism; and said coupling means being pivotally connected with said work table and with said pantograph mechanism for movements of said knee and work table in either direction along the path of knee adjustment independently of said pantograph mechanism.

ALLEN D. GUNDERSON.
